F. E. MADDUX,

SOAP DISPENSER,

APPLICATION FILED JULY 21, 1921.

1,412,883.

Patented Apr. 18, 1922.

Forrest Edward Maddux
By Walter D. Murray
Attorney

UNITED STATES PATENT OFFICE.

FORREST EDWARD MADDUX, OF PITTSBURGH, PENNSYLVANIA.

SOAP DISPENSER.

1,412,883.

Specification of Letters Patent. Patented Apr. 18, 1922.

Application filed July 21, 1921. Serial No. 486,473.

To all whom it may concern:

Be it known that I, FORREST EDWARD MADDUX, a citizen of the United States of America, and a resident of Pittsburgh, in the county of Allegheny and State of Pennsylvania, have invented a new and useful Improvement in a Soap Dispenser, of which the following is a specification.

An object of my invention is to provide a simple and efficient soap dispenser adapted to sever a section of soap from a bar.

Another object of my invention is to make a device for the purpose stated that is compact and which will not be unsightly.

These and other objects are attained by the means described herein and disclosed in the accompanying drawings, in which—

Fig. 1 is a perspective view of a device embodying my invention.

Fig. 2 is a side elevation of the device shown in Fig. 1.

Fig. 3 is an enlarged sectional view on line 3—3 of Fig. 2.

Fig. 4 is a sectional view on line 4—4 of Fig. 2.

The device A comprises a back or support a adjacent the side edges whereof are disposed the plates a' forming the sides of a hollow casing. A plate a^2 extends between the side plates a' . The plate a^2 may be made of glass if desired in order that the contents of the case may be exposed to view. A flange a^3 is formed along one edge of each of the side plates a' . These flanges are secured upon the back a by any suitable means, such as screws a^4 . U-shaped flanges a^5 are formed along the forward edge of the side plates. The grooves, formed as a result of the development of the U-shaped flanges, are exposed to one another, wherefore the front plate a^2 can be readily positioned upon the side plates so as to form a closure for the front of the casing. The U-shaped flanges a^5 terminate at a distance from the bottom of the device and at their lower ends is mounted a band a^6 extending between the side plates. The band a^6 has its lower portion turned rearwardly and upwardly upon itself, whereby a seat is formed to retain the lower end of the plate a^2 , see Fig. 2. A similar band a^7 may be employed at the top of the casing and retains the upper end of the plate a^2 . Immediately be-

low the termination of the U-shaped flanges a^5 , there is formed in each of the side plates a' , a U-shaped groove or slide-way a^8 extending transversely of the side plates, the forward walls of which project at a distance beyond the forward end of the U-shaped flanges a^5 . The portions of the side plates a' below the slideway a^8 extend in substantial alignment with the portions above the slide-way. The lowermost ends of the side plates are bent outwardly upon themselves so as to form flanges a^{10} . A plate a^{11} extends transversely of the casing below the band a^6 and is spaced from the band a^6 at a sufficient distance to permit the reciprocation therebetween of a knife a^{12} . The plate a^{11} is mounted upon upwardly struck lugs a^{24} formed on the forward ends of the flanges a^{10} . If desired the lugs a^{24} may be struck sidewardly from the side plates instead. The plate a^{11} has formed upon its lower edge, intermediate its ends, a cylindrical portion a^{13} , which cylindrical portion forms one portion of a hinge member. The knife a^{12} has formed about its side edges a cylindrical or tube-like border a^{14} which is adapted to extend into the slide-way a^8 . If desired the cylindrical border may be continued over the forward end of the knife. A knob a^{15} is mounted upon the forward end of the knife whereby the knife may be moved toward the back a . A slot a^{16} extends through the body of the knife. Pins a^{17} are mounted upon the back a and extend into the slide-way a^8 and into the tubes at the sides of the knife a^{12} . Spiral springs a^{18} are mounted upon the pins a^{17} and about the back a and the forward ends of the tube like border formed on the knife a^{12} . A door a^{19} having formed upon its forward end the complementary hinge members a^{20} , is pivotally mounted upon the hinge member formed on the plate a^{11} by means of a pin a^{21} . The door a^{19} is of sufficient width so as to extend substantially over the lower end of the passage-way formed through the casing. An arm a^{22} is mounted upon the door a^{19} and has its forward end a^{23} curved upwardly and turned upon itself so as to extend through the slot a^{16} in the knife and serving to prevent the separation of the knife from the slide-way because of the action of the springs upon said knife.

The operation of my device is as follows:

Normally the springs a^{18} retain the knife in its forward or normal position and retain the door in its normally horizontal position, as shown in the drawings. The finger a^{23} formed on the arm a^{22} is made of such length that normally the cutting edge of the knife is disposed immediately below the plate a^2 . A bar of soap is inserted in the way formed through the casing, the lower end of the bar of soap resting upon the inner surface of the door a^{19} . The distance between the door and the knife is made such that it will be equal to the desired thickness of a section of soap that is to be severed when the device is manipulated. When the knife is moved toward the back a , by exerting pressure upon the knob a^{15} , the cutting edge a^9 thereof passes through the soap and severs a section therefrom. As soon as the knife engages the bar of soap, the soap is secured by the knife and it is therefore unnecessary to retain the bar of soap by means of the door; wherefore the door is adapted to be moved about its pivotal mounting, to the position shown in dotted lines in Fig. 2. This movement of the door results from the engagement of the forward edge of the arm a^{22} engaging the forward wall of the slot a^{16} and thereby causing the arm to be projected upwardly through the slot a^{16} . As soon as the knife has completely passed through the bar of soap, the section severed will drop from the lower end of the casing. When the knob a^{15} is released, the springs a^{18} return the parts to their normal positions and the bar of soap moves downwardly and again rests upon the door a^{19} .

40 What I claim is:

1. In a soap dispensing device the combination of a casing having a passage-way through which a bar of soap may pass, a knife adapted to be projected into the passage transversely thereto, means yieldingly resisting movement of the knife into the passage-way, and a pivotally mounted door normally closing the passage-way and limiting the movement of the knife by the yielding means, the knife being adapted to move the door about its pivotal mounting when projected into the passageway.

2. In a soap dispensing device the combination of a casing having a passage-way through which a bar of soap may pass, a slotted knife adapted to be projected into the passage-way, a door pivotally mounted on the casing normally closing the lower end of the passage-way, an arm mounted on the door extending into the slot in the knife, and means yieldingly resisting movement of the knife into the passage-way.

3. In a soap dispensing device the combination of a casing having a passage-way therethrough adapted to accommodate a bar

of soap, guideways formed in the side of the casing extending transversely thereof, a knife reciprocally mounted in the guideways adapted to be moved into the passage-way and normally disposed without said passage-way, a door normally closing the lower end of the passage-way and upon which the bar of soap normally rests, adapted to be moved from its normal position, whereby the lower end of the passage-way is opened, and means 70 yieldingly resisting movement of the knife and door from their normal positions.

4. In a soap dispensing device the combination of a casing having a passage-way through which a bar of soap may pass, 80 guideways formed in the casing intermediate its ends and extending transversely of the line of movement of the bar of soap, a knife reciprocally mounted in the guideways, springs mounted in the guideways 85 abutting at their opposite ends upon the casing and the knife and normally retaining the knife without the passage-way, a door pivotally mounted on the casing normally closing the lower end of the passage-way, and a finger on the door engaging the knife adapted to be actuated by the knife, whereby the door is actuated to open and close the lower end of the passage-way.

5. In a soap dispensing device the combination of a casing having a passage-way through which a bar of soap may pass, a knife adapted to be projected into the passage-way, means yieldingly resisting movement of the knife into the passageway, means 95 limiting the movement of the knife away from the passage-way, and a door which normally supports a bar of soap and closes one end of the passage-way and which is adapted, when opened, to permit discharge 100 of a piece of soap from the casing.

6. In a soap dispensing device the combination of a casing having a passage-way through which a bar of soap may pass, a door normally closing the lower end of the 110 casing and upon which a bar of soap normally rests, a knife adapted to be projected into the passage-way and to sever from the bar of soap the lower portion thereof, and means to open the door simultaneously with 115 the severing of the portion of soap, whereupon the severed portion of soap is discharged from the casing.

7. In a soap dispensing device the combination of a casing having a passage-way 120 through which a bar of soap may pass, a knife adapted to be projected into the passage-way, a door normally closing the lower end of the passage-way, and a connection between the knife and the door whereby the 125 door is opened as the knife is projected into the passage-way and is closed as the knife is withdrawn from the passage-way.

8. In a soap dispensing device the combination of a casing having a passage-way 130

through which a bar of soap may pass, a knife adapted to be projected into the passage-way, a door normally closing the lower end of the passage-way, a connection between the knife and the door whereby the door is opened as the knife is projected into the passage-way and is closed as the knife

is withdrawn from the passage-way, and means yieldingly resisting movement of the knife into the passage-way.

10

In testimony whereof, I have hereunto subscribed my name this 18th day of July, 1921.

FORREST EDWARD MADDUX.
